CONTROL SWITCH FOR CALCULATING MACHINES

Thomas O. Mehan, Park Ridge, Ill., assignor to
Victor Adding Machine Co., Chicago, Ill., a corporation of Illinois

Application October 1, 1940, Serial No. 359,271

7 Claims. (Cl. 200—169)

My invention relates generally to calculating machines, and more particularly to improved control switch mechanisms forming parts of such machines.

It is an object of my invention to provide an improved switch means for controlling the operating cycle of an adding machine.

A further object is to provide an improved motor control switch mechanism for electric motor-driven adding machines which may be manually controlled, either by means of the operation of a suitable motor bar or by the operation of any one of a number of operation-controlling keys.

A further object is to provide an improved adding and calculating machine control mechanism which is of simple construction, may be economically manufactured, and which will have a long useful life.

Other objects will appear from the following description, reference being had to the accompanying drawings, in which:

Fig. 1 is a fragmentary plan view of the calculating machine, showing particularly the keyboard portion thereof;

Fig. 2 is a right-side elevational view of a portion of the motor control mechanism, the outer casing being shown in section;

Fig. 3 is an enlarged obliquely vertical sectional view taken on the line 3—3 of Fig. 2 and showing particularly the solenoid control switch and associated mechanism;

Fig. 4 is a vertical longitudinal sectional view taken on the line 4—4 of Fig. 3 and showing particularly the control keys;

Fig. 5 is a fragmentary vertical sectional view to a reduced scale, showing the means for releasing the key latching slides;

Fig. 6 is a generally horizontal sectional view taken on the line 6—6 of Fig. 4 and showing particularly the control slides operated by the key stems;

Fig. 7 is a generally horizontal sectional view taken on the line 7—7 of Fig. 4 showing particularly the additional slides operated by the control keys;

Fig. 8 is a fragmentary vertical sectional view taken on the line 8—8 of Fig. 3; and

Fig. 9 is a wiring diagram showing the motor control circuits.

General description

It is believed that the detailed description of the invention will be more readily understood if it is read with a knowledge of the general

construction and operation of the apparatus as a whole. The following general description is provided for this purpose.

The invention may be incorporated in any suitable electric motor-operated adding, calculating machine, or the like, but is illustrated herein as forming part of an adding machine. In general, referring particularly to the wiring diagram of Fig. 12, the apparatus comprises a motor 20 adapted to drive the adding machine through a one-revolution clutch mechanism. The motor is adapted to be energized by depression of a motor bar 54 which, when depressed, closes a switch 24. The switch 24 is adapted to complete a circuit from power supply conductors 26, 27, through the winding of a solenoid 28 and a normally closed switch 30. Energization of the solenoid 28 causes its core to move to the left, Fig. 12, and through an arm 32, link 34, and lever 36, opens the switch 30 and closes a switch 38. The switch 38 is connected between the conductor 26 and a conductor 40 through which current is supplied to the motor 20. The return circuit from the motor is through the conductor 27. A condenser 42 is associated with the motor to aid in reducing sparking across its speed governor contacts.

A switch 44 is connected in parallel with the switch 24, and is adapted to be closed for an instant each time any one of a plurality of control keys, designated generally by the reference character 46, is operated. The control keys 46 determine the character of the operation of the machine, these keys bearing appropriate legends in Fig. 1, being identified by individual reference characters as follows: 46.1—"NP"—non-print; 46.2—"NA"—non-add; 46.3—"ST-2"—sub-total second accumulator; 46.4—"T-2"—total second accumulator; 46.5—"ST-1"—sub-total first accumulator; 46.6—"T-1"—sub-total first accumulator; 46.7—"CR. BAL."—credit balance; 46.8—"REP."—repeat; 46.9—"ERR."—error.

From the foregoing description of the circuit diagram (Fig. 9), it will appear that when either the switch 24 or the switch 44 is closed, the solenoid 28 will be momentarily energized to complete the circuit to the motor 20. Upon operation of the motor 20, the lever 36 will be mechanically held in a position in which it maintains the switch 30 open and the switch 38 closed until at least one revolution of the main operating shaft has been completed. The lever 36 forms the trip lever of a suitable one revolution clutch mechanism, and is mechanically returned to normal position (thus pulling the core 84 from the solenoid 28) during the course of each operating

cycle of the machine. This one revolution clutch mechanism forms the driving connection between the motor 20 and the main shaft of the machine, and is effective to rotate the latter through one revolution upon energization of the solenoid 28. 5

The keyboard and motor bar

As shown in Fig. 1, the machine comprises a casing 43, which may be of any suitable construction, and banks of numeral keys 45. In 10 addition, there are provided add and subtract control keys 47 for the second accumulator, these keys bearing the appropriate legends "2A" and "2S," but which will usually be differentiated by being of different colors. A release key 48 is provided for the two keys 47. A subtract key 50 is provided to condition the machine for subtracting on the first accumulator.

The manually operated means for controlling the operation of the motor in normal adding and subtracting operations comprises a pair of rigid generally U-shaped bars 52 and 54, together forming a rectangle entirely surrounding the keyboard. The ends of the bar 52 are joined by a transverse member 56 to increase the rigidity of the bar 52. The bar 52, as shown in Fig. 2, is pivoted upon a pair of shouldered screws 58 threaded in lugs forming part of a key plate 60. (The screw 58 at the left-hand side of the motor bar 52 is not shown in the drawings.) Similarly, the key bar 54 has rearwardly extending portions which are pivoted upon shouldered screws 62, likewise threaded in the key plate 60. A motor bar stem 64 has its upper end positioned beneath the key bar 52 and is guided for reciprocatory movement by a pair of studs 66, 67, secured in an outer section plate 68, the studs 66 and 67 projecting through elongated slots 69 formed in the key stem 64. A tension spring 70 normally holds the stem 64 in its uppermost position, and thus holds the motor bars 52 and 54 in their normal positions, as shown in Fig. 2, since the motor bar 52 has a pin and slot connection with the bar 54. This connection comprises a pin 72 riveted in the motor bar 52 and projecting into a slot 74 formed in the rearwardly extending arm portion of the motor bar 54. There is a similar connection between the forwardly extending left-hand portion of the motor bar 52 and the left-hand rearwardly extending arm portion of the motor bar 54, as indicated in dotted lines in Fig. 1 and as further shown in Fig. 5.

Due to this interconnection between the bars 52 and 54, depression of either of these bars will cause the stem 64 to be moved downwardly 55 against the tension of its spring 70. Furthermore, the operator of the machine may press upon any portion of either of the motor bars 52 or 54 to accomplish this result. This is of great convenience for skilled operators, since it enables them to initiate an operating cycle of the machine immediately following the depression of the last numeral key, irrespective of the position of such key, without moving the hand appreciably.

It will be noted that the lower end of the stem 64 overlies an insulating strip 76 attached to one of the contact arms of the switch 24, the switch 24 being suitably secured to the outer section plate 68 by a bracket 78.

Control key operated switch mechanism

As above indicated, the solenoid 28 may be energized not only by depression of one of the motor bars 52 or 54, but also by operation of any one of the control keys 46.1 to 46.8. As best

shown in Fig. 4, each of the control keys is provided with a key stem 152, each having a forward cam projection 154. The key stems 152 are suitably guided in slots formed in key stem plates 156 and 158 and are resiliently urged to their uppermost positions, as shown in Fig. 4, by coil springs 160 which extend through a horizontal row of key stems and are anchored at their ends. One of the coil springs 160 thus serves as a key return spring for a horizontal row of keys.

The key stems 152 are also guided and the length of their strokes limited by rods 161 which project through elongated slots 163 formed in the key stems, the rods 161 extending through the 15 slots 163 of a horizontal row of key stems and being suitably secured in position.

The cam projections 154 are adapted, upon depression of the keys 46 successively to engage slides 162, 164, as shown in Figs. 4 and 6. The 20 key stems 152, for the keys 46.1, 46.3, 46.5, 46.7, and 46.9, engage shoulders 166 formed at the sides of these slides 162 and 164, while the key stems 152, for the keys 46.2, 46.4, 46.6, and 46.8, project through slots 168 formed in the slides 162 and 164. The slide 162 is pulled rearwardly by a tension spring 170 which is suitably tensioned between an anchoring stud 171 and a lug 172 struck upwardly from the slide 162.

The forward end of the slide 164 (Fig. 8) is 30 engageable with the upwardly extending arm 174 of a latch 176 forming part of a bail 177. The latch 176 is urged clockwise, by a suitably anchored spring 178, into latching engagement with a stop shoulder on a stepped actuator bar 180, as will be more fully described hereinafter. The spring 178 serves to urge the slide 164 rearwardly. The slide 162 has a forwardly extending projection 182, while the slide 164 has a similar but shorter forward projection 184 (Fig. 4).

40 The switch 44, previously described with reference to the circuit diagram of Fig. 12, is formed by a pair of resilient switch arms 185, 186 (Figs. 3 and 6). The switch arm 185 has an insulating strip 187 riveted or otherwise suitably secured thereto, while the switch arm 186 has a similar strip of insulating material 188 secured thereto. The forward projection 182 is normally in position engaging the strip 187, while the projection 184 of the slide 164 terminates adjacent the inner surface of the insulating strip 188.

50 When a key, for example the key 46.3, is depressed, its camming projection 154 first moves the slide 162 forward (to the left, Figs. 4 and 6), thereby further separating the normally separated contacts of the switch 44. As the camming surface of the projection 154 engages the shoulder 166 of the slide 164, the latter will also be cammed forwardly, but will move at substantially the same speed as the slide 162 until the camming projection 154 has passed beneath the slide 162, as the key stem reaches the lower limit of its stroke. When this occurs, the latching slide 162 will be pulled rearwardly (to the right, Fig. 4) by its spring 170 and its shoulder 166 will thus overlie the projection 154 and hold the key in depressed position. It will be noted, however, that when the key is in depressed position, the slide 164 will remain in its forward position so that the rearward movement of the slide 162 will result in closure of the switch 44.

55 As previously explained, particularly with reference to Fig. 9, the closure of the switch 44 results in the energization of the winding of the solenoid 28 and causes the operation of the machine through at least one complete cycle. In

this respect, the closure of the switch 44 has the same effect as the closure of the switch 24, since it will be noted that these two switches are connected in parallel.

The purpose of the error key 46.9 is merely to release keys (such as the numeral keys 45 or the control keys 46.1, 46.2, and 46.8) which have been accidentally or inadvertently depressed. For this reason, the slide 164 does not have a shoulder 166 to be engaged by the camming surface 154, and for similar reasons, the key stem of this key does not have a notch above its camming projection 154. Thus, upon depression of the error key, only the slide 162 will be moved forwardly (to the left, Fig. 4), while the slide 164 will remain stationary. As a result, the contacts of the switch 44 will merely be separated further upon the depression of the error key 46.9, and any depressed numeral keys (as will appear hereinafter) or the repeat key 46.8 will be released.

It will be understood that as long as any of the keys 46.3 to 46.7 remains depressed, it will hold the slide 164 in its left-most (Fig. 4) position, and through the projection 184 of the slide maintain the switch 44 closed.

As is more fully disclosed in my copending application Serial No. 372,289, filed December 30, 1940, the position of the stepped actuator bar 180 determines the character of the operating cycle of the machine, i. e., whether it shall be an adding, subtracting, sub-total, total or other type of cycle. The subtract key does not operate any stop to limit the extent of rearward movement of the stepped actuator bar but permits it to move a full stroke rearwardly, which results in conditioning the machine for a subtracting operation.

The lower extremities of the key stems 152 for the keys 46.1 to 46.7 are adapted when depressed to form stops limiting the degree of rearward motion of the stepped actuator bar 180, and thus determine the character of the ensuing cycle.

When a total, sub-total, or credit balance is to be taken, the appropriate key 46 is depressed, and depression of this key not only results in conditioning the machine to go through a cycle of the character determined by the depressed key, but also results in closure of the switch 44, thereby initiating an operating cycle. It will be understood that the character of the cycle is determined by the distance that the stepped actuator bar 180 is permitted to move rearwardly during the first portion of the operating cycle, this distance being, of course, determined by the engagement of stop lugs on the stepped actuator bar with the ends of the depressed keys.

While a particular embodiment of my invention is disclosed herein, it will be apparent to those skilled in the art that numerous changes and variations may be made in the construction without departing from the underlying principles of the invention. I therefore desire, by the following claims, to include within the scope of the invention all such equivalent structures as may be readily devised by those skilled in the art to accomplish substantially the results of my invention by substantially the same or equivalent means.

I claim:

1. In an adding machine having a driving electric motor, a switch for controlling the supply of current to said motor, said switch comprising a pair of flexible resilient contact arms, a movable control element manually movable from normal position and having a cam surface, a pair of slides engageable by said cam, one of said slides constituting a latch to hold said element displaced from its normal position, and means on said slides engageable respectively with said switch contact arms, whereby both of said switch arms will be flexed in the same direction by said slides during the initial portion of the movement of said control element and said switch arms will be able to move toward each other to make contact only upon movement of said latching slide to latching position.
2. In an adding machine having a driving electric motor, a switch for controlling the supply of current to said motor, said switch comprising two movable parts, a manually depressible control key, a stem for said key having a saw-tooth cam projection, a pair of slides having portions lying in the path of downward movement of said cam, said slides being located sufficiently close to each other to be simultaneously engaged by said cam, the upper one of said slides serving to latch said key in depressed position, resilient means to resist movement of said slides by said cam, and means moving with said slides to engage said switch parts, moving them in the same direction as the slides are moved by said cam projection and permitting said parts to move toward each other as said latching slide moves to latching position over said cam projection, thereby to complete a circuit to supply current to said motor only after said key has been latched in depressed position.
3. In a calculating machine having a driving electric motor, a switch controlling the energization of said motor, said switch comprising a pair of normally spaced resilient switch arms, a depressible control key, latching means for holding said key in depressed position, and means operated by said latching means to effect contact between said switch arms only after said latching means has moved to latching position.
4. In a calculating machine having a driving electric motor, a switch controlling the energization of said motor, a depressible key, a latch to hold said key in depressed position, and means operated by said latch to effect closure of said switch only after said latch has moved to a position in which it holds said key depressed.
5. In an adding machine having a driving electric motor, a motor operation controlling circuit, a switch in said circuit, a control element manually movable from normal position, latching means engaged by said element to hold the latter displaced from its normal position and having a part cooperable with said switch for operating the latter, and means to prevent operation of said switch by said manually movable element prior to movement of said latching means to latching position.
6. In an adding machine having a driving electric motor, a motor operation controlling circuit, a switch in said circuit, a manually operable control member movable from normal position to a fully operative position, said member having a cam surface formed thereon, a pair of movable elements successively engaged by said cam surface upon movement of said control member, one of said elements constituting a latch for holding said control member in its operative position, and means to effect closure of said switch only when said latter element is in latching engagement with said control member.
7. In a calculating machine having an electric driving motor, a motor operation controlling circuit, a switch in said circuit, said switch having

two relatively movable parts, a control member manually movable from normal position to operative position, a cam on said member, and a pair of elements cooperable with said cam and each engaging one of said switch parts, said elements being moved in the same direction by said cam during the major portion of the movement of

5 said control member from its normal to its operative position, and one of said elements being movable relative to the other to latch said control member in its operative position, thereby to cause relative movement of said switch parts and consequent closure of the switch.

THOMAS O. MEHAN.
